Inventor

A. B. Clay, Jr.

By *Clarence O'Brien*
Attorney

UNITED STATES PATENT OFFICE.

ANDREW BURTON CLAY, JR., OF BUNCETON, MISSOURI.

OIL BURNER.

Application filed October 3, 1925. Serial No. 60,256.

To all whom it may concern:

Be it known that I, ANDREW BURTON CLAY, Jr., a citizen of the United States, residing at Bunceton, in the county of Cooper and State of Missouri, have invented certain new and useful Improvements in an Oil Burner, of which the following is a specification.

The present invention relates to an oil burner, and has for its principal object to provide a structure wherein the oil is heated and vaporized first before being mixed with air, wherein the air to be mixed with the vaporized oil is also pre-heated.

An important object of the invention is to provide a burner of this nature having superior compactness, and convenience in construction, one which is exceedingly simple, durable, efficient and reliable in use, inexpensive to manufacture, and otherwise well adapted to the purpose for which it is designed.

With the above and numerous other objects in view as will appear as the description proceeds, the invention resides in certain novel features of construction and in the combination and arrangement of parts as will be hereinafter more fully described and claimed.

In the drawing

Figure 1 is a top plan view of the burner embodying the features of my invention, and

Fig. 2 is a fragmentary longitudinal section therethrough.

Referring to the drawing in detail, it will be seen that 5 designates a pan which is provided on its bottom with a plurality of vertical conical shaped recesses 6 with the apexes of which communicates a plurality of tubes 7. A conduit 8 is curved at one end and has one terminal 9 passing through the center of the bottom of the pan 5, while the other end thereof extends thru a recess 10 formed in one end wall of the pan 5. The horizontal portion of this conduit 8 is provided with a tapered bore as is indicated to advantage in dotted lines in Fig. 2. A casting 11 has a mixing chamber formed therein. Air pipes 12 are connected with the mixing chamber 11 and pass through the ends of the pan 5 over the bottom thereof.

An oil pipe 13 passes up through the bottom of the pan 5 and is coiled about the conduit 8, that is the horizontal portion thereof,

as is indicated at 14, and is then coupled with the mixing chamber casting 11 by a suitable coupling means 15.

A distributor is located below the pan 5 and includes an inner conical-shaped portion 17 and an outer conical-shaped member 18. The base end of the member 17 is provided with an outwardly extending flange 19 on which is adapted to rest an inwardly extending flange 20 on the base portion of the outer member 18. The apex of the member 17 terminates within the bore of the conduit 8, while the apex portion of the member 18 is threadedly engaged as at 21 with the lower end of the conduit 8. The plurality of tubes 7 pierce the outer member 18 and communicate with the space 22 provided between members 17 and 18.

Drain pipes 24 pierce the member 17 at the bottom portion thereof and lead downwardly therefrom. When the burner is in operation, the oil flows through the pipe 13 about the conduit 8 in the coil 14 and is vaporized by the heat of the burner in the pan 5. The oil is then mixed with air within the mixing chamber casting 11 and is injected into the conduit 8 into the distributor. The vapor reaches the space 22 provided between the members 17 and 18 and is distributed to the tubes 7 and burns in the recesses 6. Any condensation of the vapors will drain downwardly through the drain pipes 24, as is obvious.

The construction, operation, and utility of the invention, will now be clearly understood without a more detailed description. It is desired to point out, however, that the arrangement of the parts is very compact and convenient so that the burner takes up very little space when in actual operation. Furthermore the parts thereof are readily accessible and are very simple.

The present embodiment of the invention has been disclosed merely by way of example since in actual practice it attains the features of advantage enumerated as desirable in the statement of the invention and the above description. It will be apparent that numerous changes in the details of construction, and in the combination and arrangement of parts may be resorted to without departing from the spirit or scope of the invention as hereinafter claimed, or sacrificing any of its advantages.

Having thus described my invention, what I claim as new is:—

1. An oil burner of the class described including a pan, means for pre-heating the oil in relation to the pan, a distributor for receiving the oil from said means including a pair of conical-shaped members, one within the other to provide a space therebetween, and a plurality of tubes piercing the outer member and the bottom of the pan.
2. An oil burner of the class described including a pan, means for pre-heating the oil in relation to the pan, a distributor for receiving the oil from said means including a pair of conical-shaped members, one within the other to provide a space therebetween, a plurality of tubes piercing the outer member and the bottom of the pan, drain pipes piercing the inner member and extending downwardly therefrom.
3. An oil burner of the class described including a pan, a conduit extending through the bottom of the pan and curved to extend beyond one end thereof, a mixing chamber casting on the outer end of the conduit, air pipes communicating with the mixing chamber casting and extending through the pan, an oil pipe coiled about the conduit and communicating with the mixing chamber casting, a distributor at the bottom end of the conduit and below the pan including a pair of conical-shaped members, one within the other and spaced from each other, a plurality of tubes piercing the outer member and the bottom of the pan, drain pipes piercing the inner member at the base end thereof and extending downwardly therefrom.
4. An oil burner of the class described including a pan, a conduit extending through the bottom of the pan and curved to extend beyond one end thereof, a mixing chamber casting on the outer end of the con-

duit, air pipes communicating with the mixing chamber casting and extending through the pan, an oil pipe coiled about the conduit and communicating with the mixing chamber, a distributor at the bottom end of the conduit and below the pan including a pair of conical-shaped members, one within the other and spaced from each other, a plurality of tubes piercing the outer member and the bottom of the pan, drain pipes piercing the inner member at the base end thereof and extending downwardly therefrom, the inner member provided at its base end with an outwardly extending flange, the outer member provided at its base end with an inwardly extending flange adapted to rest on the first mentioned flange.

5. An oil burner of the class described including a pan, a conduit extending through the bottom of the pan and curved to extend beyond one end thereof, a mixing chamber casting on the outer end of the conduit, air pipes communicating with the mixing chamber casting and extending through the pan, an oil pipe coiled about the conduit and communicating with the mixing chamber, a distributor at the bottom end of the conduit and below the pan including a pair of conical-shaped members, one within the other and spaced from each other, a plurality of tubes piercing the outer member and the bottom of the pan, drain pipes piercing the inner member at the base end thereof and extending downwardly therefrom, the inner member provided at its base end with an outwardly extending flange, the outer member provided at its base end with an inwardly extending flange adapted to rest on the first mentioned flange, the upper end of the outer member being threadedly engaged with the lower end of the conduit.

In testimony whereof I affix my signature.
ANDREW BURTON CLAY, JR.
